UNITED STATES PATENT OFFICE.

ENGELBERT MUELLER, OF RESERVE TOWNSHIP, ALLEGHENY COUNTY, PENNSYLVANIA.

ARTIFICIAL LIMB.

963,797.

Specification of Letters Patent.

Patented July 12, 1910.

Application filed December 6, 1909. Serial No. 531,558.

To all whom it may concern:

Be it known that I, ENGELBERT MUELLER, residing in Reserve township, in the county of Allegheny and State of Pennsylvania, a citizen of the United States, have invented or discovered certain new and useful Improvements in Artificial Limbs, of which improvements the following is a specification.

My invention relates to improvements in artificial limbs.

The object of my improvement is generally to provide for the removal of one member, for example a foot member, and the replacement of it by another member, for example a peg member.

In an application filed by me September 7th, 1909, Serial No. 516,469, I have shown and described an artificial leg and foot articulated together and having certain novel features.

My present invention is here illustrated as supplementary to the construction which is therein shown and described.

Figure 1 is a view in side elevation identical with one of the figures of the application referred to, of an artificial leg and foot articulated one to the other. Fig. 2 is a vertical section illustrating a leg member of Fig. 1, but in place of the foot member which in Fig. 1 is shown articulated to it, a peg member is articulated to it. In Fig. 3 is shown on larger scale particular means for articulating the parts together such as I have described in the earlier application referred to.

While for ordinary usage it is desirable to have the foot of an artificial leg pivoted to the leg itself, that in use the foot may have a certain movement like the movement of a natural foot upon the ankle joint, a user may at times desire to have what is called a "peg leg," that is a leg which ends with a blunt tip with no pivoted foot upon it. Such a peg leg is useful for rough walking and in rough working generally.

My present invention consists more particularly in the shaping of a peg member and the application of the peg member in place of the foot member of an artificial leg, in which the leg body and the foot are pivoted to one another.

Referring to Figs. 1 and 2, the leg member of the artificial leg is illustrated at 1; a foot member is shown at 2 in Fig. 1, and a peg member is shown at 3 in Fig. 2. In Fig. 1

the foot member 2 is articulated to the leg member 1 by the particular means which are shown in Fig. 3. They consist of two bolts, 4 and 5, which extend longitudinally in the leg member and the foot member, respectively. Their heads, 6 and 7, protrude from the leg member and the foot member, respectively, and these heads are in shape complementary hinge-knuckles, that is they are shaped to engage one another when brought together, to receive a hinge-pin which shall unite them. These bolts are preferably secured in place by nuts at their opposite ends and by the tightening and loosening of the nut upon one of these bolts, the pivot-pin, which when the parts are assembled unites the two members of the joint, is drawn against the adjacent surface of the body of the member, to the end that the pivot-pin is held immovable relative to that member, while the other member swings upon it. This detail of the pivoting is however no part of my present invention; it is described and claimed in the earlier application referred to.

For the purposes of the present invention, it is sufficient to note that in such way the foot is articulated with the leg, being preferably pivoted thereon. It is further to be noted that, to the end that the foot may have pivotal movement relative to the leg, the adjacent surfaces of the body of the leg member and the foot member must permit of such pivotal play. To this end, the surfaces 8 and 9 of the bodies of the leg member and the foot member respectively, adjacent to the pivot-joint, are, as indicated in Fig. 1, so shaped as to allow a certain amount of play. The foot member, so described, is detachable from the leg member simply by drawing the pivot-pin. If the pivot-pin be secured by the tightening of one of the bolts, it is of course necessary to loosen that bolt before the pivot-pin may be drawn. I provide also what I call the peg member, illustrated at 3 in Fig. 2. It is attached to or articulated to the leg member 1 in precisely the same manner as the foot member is articulated thereto, that is by being provided with a bolt 5, extending longitudinally through it, and with a head forming a hinge-knuckle complementary to the hinge-knuckle on the bolt 4, which the leg member carries, and pivoted thereon by a pivot-pin. It is not however

ordinarily desirable to have this peg member swing pivotally on the leg member, and to that end, instead of shaping the surface of the peg member adjacent to the pivot joint so as to permit of pivotal play, the surface of the peg member is shaped to form a surface of contact of considerable extent with the surface of the leg member, adjacent to the point of articulation when the parts are assembled. This is indicated at 10 in Fig. 2. The body of this stump member is preferably made of rigid material, such as soft wood, and is preferably covered with rawhide. Its lower end, that is the end or face which forms the bearing, is preferably elastic, and to this end I conveniently form a socket in the lower face of this peg member, which socket is preferably lined with a metallic sleeve 11, and into this socket I insert a bearing block 12, preferably made of india-rubber. I preferably secure the bolt 5 by having it protrude into this socket, and I preferably so shape and proportion the parts that the bolt 5 is a counterpart of the bolt 5 used in securing the foot member when desired, and accordingly a single bolt 5 is all that is necessary, for the user of this alternative foot and peg construction, may then remove the foot by merely loosening the nut 30 and may then apply the peg member in its place and secure it by applying the nut again.

It will be understood that the dimensions are such that the length of the leg is substantially the same whether the foot member or the stump member be applied at its lower end, allowance however being made for a shoe which is ordinarily worn upon an artificial foot.

40 By way of further adapting my artificial leg to rough usage when the stump member is applied, I ordinarily provide a boot 13, preferably of leather, covering the joint between the stump member and the leg member.

I claim herein as my invention:

1. In an artificial leg, the combination of a leg member, a foot member, and a peg

member, each of said members provided with a joint part, the joint parts carried by said foot member and said peg member being severally complementary in shape to the joint part carried by said leg member, substantially as described.

2. In an artificial leg, the combination of a leg member, a foot member, means for pivotally and removably articulating said leg and foot members, a peg member, and means for rigidly but removably articulating said leg and peg members, the said foot member and the said peg member being interchangeable in their application to said leg member, substantially as described.

3. In an artificial leg, the combination of a leg member provided with a hinge-knuckle, a foot member, a peg member, and a second hinge-knuckle complementary to the first adapted for application to both the foot and peg members removably applied to said foot member or said peg member as desired, and a hinge-pin completing the joint when two of said members with their complementary hinge-knuckles are brought together, substantially as described.

4. In an artificial leg, the combination of a leg member and a peg member engaging one another over extended contacting surfaces, complementary articulating parts carried by each of said members and engaging one another when the said members are brought together over such contacting surfaces, substantially as described.

5. A peg member for an artificial limb consisting of a body portion provided with a surface of contact and with a socket, a bolt passing through said body portion from said surface of contact to said socket, and a bearing block engaged by and protruding from said socket, substantially as described.

In testimony whereof, I have hereunto set my hand.

ENGELBERT MUELLER.
